UNITED STATES PATENT OFFICE.

ERNEST GRAHAM PULLUM, OF LONDON, COUNTY OF MIDDLESEX, ENGLAND,
ASSIGNOR TO VIRGOE, MIDDLETON & CO., OF SAME PLACE.

SUSPENDER-END.

SPECIFICATION forming part of Letters Patent No. 393,581, dated November 27, 1888.

Application filed September 6, 1888. Serial No. 284,741. (No model.) Patented in England September 8, 1887, No. 12,173.

To all whom it may concern:

Be it known that I, ERNEST GRAHAM PULLUM, of London, in the county of Middlesex, England, have invented a new and useful Improvement in Connections for Suspender-Ends and other Portions of Garment-Supporters, (for which Letters Patent of the United Kingdom of Great Britain and Ireland, No. 12,173, have been granted and dated September 8, 1887,) of which the following is a specification.

The object of the invention is to enable the wearer to easily and quickly disconnect the parts of the suspender or garment-supporter without the necessity for removing or unfastening the coat, vest, or outer garment and without unbuttoning the ends or tabs from the trousers or garment suspended, and thereby unnecessarily wearing or tearing the button-holes or subjecting the buttons to unnecessary liability to be torn off.

To this end the invention consists, essentially, in a novel construction of a spring-snap, one member of which is permanently attached to a buckle or link on the main portion of the suspender or brace, and the other member is permanently attached to the ends or tabs, which are buttoned to the waistband of the garment.

The invention is illustrated in the accompanying drawings, in which—

Figure 1 is a face view showing the parts in position for use. Fig. 2 is an edge view of the upper member of the snap attached to a buckle on the main portion of the suspender. Fig. 3 is a longitudinal sectional view taken in the line $x-x$ of Fig. 1. Fig. 4 is an end view of the upper member of the snap, and Fig. 5 an end view of the lower member. Fig. 6 is a partly-sectional view showing the form and construction of the parts and their positions when connected together.

Similar letters of reference designate corresponding parts in all the figures.

A designates the upper member of the snap, and B B² designate the lower member.

C designates the strap or webbing, which forms the main portion of the suspender or brace, and D D the tabs or "suspender-ends," which are provided with button-holes for engagement with the buttons on the garment.

E is a buckle on the shoulder-strap C.

The upper member, A, of the snap, which is to remain attached to the strap C, consists of a box or socket, and is represented as made of a metal plate doubled midway of its length, so as to surround or hook over one of the sides of the frame of the buckle E or a slide or link attached to or carried by the strap C. One portion of the plate is continued downward in the same plane from the doubled portion to form the back of the socket, and the other portion is continued downward parallel with the first-named portion to form the front of the socket. The lower corners of the said front and back portions of the doubled plate are provided with lugs a², which are turned inward and bent so as to hook into each other, for the purpose of holding the front and back portions of the plate permanently in place to complete the socket and to form shoulders or bearers on opposite sides of the socket, with openings a above them, as shown in Figs. 2 and 6, for the engagement of spring-actuated catches or slides G, to be presently described, in the lower member of the snap.

The lower member of the snap, to which the suspender ends or tabs are connected permanently, consists of a socket, B B², two sliding catches, G G, partly contained therein, but projecting through openings in the sides thereof, and a spiral spring, s, interposed between said catches. The said socket has a loop, l, at its bottom for the attachment of the tabs D D. The said catches G G have on the outer sides of their upper part beveled latch-like projections g, which project through openings in the upper part of the ends of the box or socket B B², and which may pass between the lugs a² of the socket A and slip through the holes a above, and so be caused to engage with the shoulders formed by the upper edges of said lugs, as shown in Fig. 6, by the pressure of the spring s. The said catches have also on their lower parts outward projections g², which always protrude, as shown in Figs. 1 and 6, through openings in the sides of the socket B B². By taking these projections between the thumb and finger and pressing them inward they are disengaged from the shoulders of the lugs a, and the entire lower member of the

100

strap with the attached tabs D D are detached from the upper member, which remains attached to the shoulder strap or brace.

To attach the tabs or ends to the shoulder strap or brace, the lower member of the snap is presented to the opening in the bottom of the socket A with the bevels of the latches g against the lower edges of the lugs a², and from this position it is pushed upward. The latches are thus caused to pass between the said lugs a² until they pass over the shoulders formed by the upper edges thereof and slip out through the openings a, forming a perfect lock until it is desired to detach the parts again, when it is only necessary to press inward the ends g² of the catches and pull apart the upper and lower parts of the connections.

The socket B B² is represented as made of two flat plates, B and B², fastened together by turning their upper and lower edges inward and lapping and clamping them together, as shown at b b in Fig. 3. The back plate, B, is represented as having provided in it, as shown in Fig. 3, an internal recess for the reception of the spring s.

What I claim as my invention, and desire to secure by Letters Patent, is—

1. The snap-hook connection herein described for two portions of a suspender or garment-supporter, one member of which consists of a box or socket having lugs or shoulders in opposite sides, and the other member of which consists of a box or socket, two sliding catches arranged within said box or socket and protruding through openings in opposite sides thereof, and a spring interposed between said catches to force them both outward into engagement with the lugs or shoulders of the first-named member, substantially as herein described. 30

2. The combination of the box or socket A, having openings a and lugs or shoulders a² a² on opposite sides, the box or socket B B², the sliding catches G G, contained in said box or socket B B², and having the protruding latch-like projections g g on their upper parts and thumb and finger projections on their lower parts, and the spring s, interposed between the said sliding catches, all substantially as and for the purpose herein described. 35
